[57] **CLAIM**

The ornamental design for a housing for a plug-in printed circuit board, as shown and described.

DESCRIPTION

FIG. 1 is a front and upper right isometric view of a housing for a plug-in printed circuit board showing my new design;

FIG. 2 is a top view of the design;

FIG. 3 is a bottom view of the design;

FIG. 4 is a front view of the design;

FIG. 5 is a right side elevation of the design;

FIG. 6 is a left side elevation of the design; and,

FIG. 7 is a rear view of the design. The broken line showing is included for the purpose of illustrating environmental structure only and forms no part of the claimed design.

FIG. 4

FIG. 2

FIG. 1

FIG. 3

FIG. 6

FIG. 7

FIG. 5
